UNITED STATES PATENT OFFICE.

WILLIAM GENTRY SHELTON, OF ST. LOUIS, MISSOURI.

HAIR-CURLING DEVICE.

Application filed May 7, 1926. Serial No. 107,346.

This invention relates to hair-curling devices, and more particularly to a device on which the hair is wound by hand and then tightened by imparting a rotary motion to 5 one of the elements of the device. The main object of the invention is to produce a simple, efficient and durable device of this kind.

More specifically stated, an object is to provide the device with a very effective 10 means to prevent retrograde motion of the rotary element. A further object is to produce a device of this kind including a tube containing a rotatable rod with an operating member at one end, and a simple connecting 15 means whereby the operating member is secured to the tube to prevent longitudinal displacement of the rod. This connecting means preferably comprises a sleeve screwed onto the operating member and interlocked 20 with the tube, so as to permit rotation of the operating member and at the same time prevent longitudinal displacement of the rod to which the operating member is secured.

With the foregoing and other objects in 25 view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

35 Fig. I is a side elevation of a hair-curling device embodying the features of this invention, showing a strand of hair wound around the tube.

Fig. II is an enlarged longitudinal section 40 of the device.

Fig. III is an enlarged section on line III—III in Fig. II.

Fig. IV is an enlarged section showing the means for connecting the operating member 45 to the tube and the spring to prevent retrograde motion of the rod.

To illustrate the invention, I have shown a tapering tube 1 containing a rod 2 which extends from the lower end of the tube. The 50 extended lower end of the rod is forked, as shown at 3, to receive a string 4 whereby the hair is secured to the rod.

The upper end of the rod is provided with an operating member comprising a knurled 55 knob 5 having a reduced extension 6 which

is formed integral with or otherwise suitably secured to the rod 2. This extension 6 is threaded to receive an internally threaded sleeve 7 having an inturned flange 8 which lies in an annular groove in the outer face 60 of the tube. The sleeve 7 is thus rotatably interlocked with the tube 1 to prevent longitudinal displacement of said sleeve, and since the sleeve is secured to the operating member 5, it prevents longitudinal displacement of 65 the rod 2 in the tube.

The rod and its operating member 5 are to be turned in a clockwise direction so the extension 6 is provided with a right-hand thread to prevent unscrewing of the sleeve 7. 70 This sleeve engages an abutment shoulder at the junction of knob 5 and the extension 6, so as to limit the rotary motion of the threaded sleeve relative to the knob 5. The lower end of the extension 6 is separated 75 from the tube 1 and it cannot contact with said tube. Therefore, the knob 5, its extension 6 and the sleeve 7 rotate as a unit with very little resistance due to friction between this unit and the tube.

The means for preventing retrograde motion of the rod 2 in the tube 1 comprises a spring 9 interposed between said rod and tube. This spring is preferably in the form of a leaf or flat strip of metal coiled around the rod and having its inner end secured to the rod in any suitable manner, for example, by means of a rivet 10 shown in Fig. III. The outer end of this spring comprises a coil member surrounding the inner end and 80 frictionally engaging the inner face of the tube 1.

Attention is directed to Fig. III which shows how the outer end portion of the spring conforms to and contacts with the 95 tube. The spring tends to expand while confined by the tube, but it will slide freely on the tube when the rod is turned in a clockwise direction, for this motion tends to contract the spring. However, any effort 100 to turn the rod in the opposite direction will tend to expand the spring, and such rotation is therefore positively prevented by the pressure of the outer end of the spring on the inner face of the tube.

The lower portion of the tube 1 contacts with the rod 2, but the upper portion of said tube is formed with a relatively large bore, or opening, to receive the spring 9. The rod and its operating member, together 105 110

with the spring 9, can be easily applied to, or withdrawn from, the tube 2 and sleeve 7, and this spring provides a strong, durable and positive means to prevent retrograde motion of the rod in the tube.

In using the device, the hair is secured to the lower end of the rod 2 by means of the string 4, and the hair is wound by hand around the tube 1. The upper end of the hair can then be secured by means of a string as shown in Fig. I, or in any other suitable manner. The next step consists in tightening the hair on the tube, and this can be accomplished by firmly holding the tube 1 and turning the knob 5, or by holding the knob and turning the tube. During the tightening operation, the spring 9 prevents retrograde motion, and after this operation is completed the spring will securely hold the hair in its tightened condition for an indefinite period.

I claim:

1. A hair-curling device comprising a tube on which the hair is wound, a rod rotatably mounted in said tube, said rod having an end extending from the tube and adapted to be secured to the hair, and a leaf spring in the form of a coil tending to expand between said rod and tube to prevent rotation in one

direction, said leaf spring having an inner end secured to said rod and an outer coil member surrounding said inner end and conforming to the inner face of said tube, and said outer coil member being in frictional contact with the inner face of said tube. 30

2. A hair-curling device comprising a tube on which the hair is wound, a rod rotatably mounted in said tube, said rod having an operating member at one end located outside of said tube, the other end of said rod being 40 extended from the tube and adapted to be secured to the hair, means for preventing retrograde motion of the rod in the tube, and means for preventing longitudinal displacement of the rod, the last mentioned means including a sleeve connecting said operating member to said tube, said sleeve being screwed onto said operating member and provided with an inturned flange at its lower end, the tube having an annular groove 50 in which said flange is mounted and the operating member being provided with an abutment engaged by said sleeve to limit the rotary motion of the sleeve relative to said operating member. 55

In testimony that I claim the foregoing I hereunto affix my signature.

WILLIAM GENTRY SHELTON.
